UNITED STATES PATENT OFFICE.

FRANK A. BRACKETT, OF MANCHESTER, NEW HAMPSHIRE, ASSIGNOR TO W. H. McELWAIN COMPANY, A CORPORATION OF MASSACHUSETTS.

SEWING-MACHINE.

1,301,808.

Specification of Letters Patent. Patented Apr. 29, 1919.

Application filed May 21, 1917. Serial No. 169,917.

To all whom it may concern:

Be it known that I, FRANK A. BRACKETT, a citizen of the United States, and a resident of Manchester, county of Hillsborough, and 5 State of New Hampshire, have invented an Improved Sewing-Machine, of which the following is a specification, reference being had to the accompanying drawings, forming part thereof.

10 This invention has reference to improvements in sewing machines adapted for use in attaching lip forming strips or members to insoles.

One object of the invention is to provide 15 a sewing machine of suitable construction with means for progressively operating on an insole and a lip forming strip that said strip may be so folded as to provide a duplex upstanding lip having extensions to 20 receive the lines of sewing stitches and that, subsequent to the sewing operation said lip may be deflected or bent over one of said extensions whereby a channel lip is provided.

25 Other objects of the invention will appear from the following description.

The invention consists in the novel means for progressively operating on the strip of material to form a lip and for applying and 30 holding said lip to the sole during the sewing process.

The invention also consists in the means for turning, bending or forming said lip, after its attachment to the sole, to constitute 35 an inclined or channel member.

The invention also consists in such other 40 novel features of construction and combination of parts as shall hereinafter be more fully described and pointed out in the claims.

Figure 1, represents the invention as applied to an ordinary sewing machine adapted to sew a series of lines of stitches, it being understood that the parts of the machine 45 not shown are of any well known construction and operation.

Fig. 2, represents a view of parts of the same at right angles with Fig. 1.

50 Fig. 3, represents a sectional view of parts of the apparatus taken on line 3—3 Fig. 1 to show the cross sectional shape of the lip member and its relation to the sole at the sewing position.

Fig. 4, represents a sectional view of por-

tions of the sole and its completed channel 55 lip member as on line 4—4 Fig. 1.

Fig. 5, represents a plan view of the work support and parts related thereto.

Fig. 6, represents a sectional view of the strip folding guide and sustaining device 60 as taken on line 6—6 Fig. 5.

Fig. 7, represents a cross sectional view taken on line 7—7 Fig. 6.

Fig. 8, represents a plan view of the lower folder guide member showing the work support. 65

Fig. 9, represents a bottom plan view of the upper guide member.

Fig. 10, represents a rear end view of the folder guide. 70

Similar characters of reference designate corresponding parts throughout.

The material to be operated on by this improved machine usually consists of a sole A of leather, leatherboard, cork or other suitable material usually quite stiff, and a strip of tape B preferably of canvas or other woven fabric for which however any other suitable material may be substituted. In view of the nature of the materials sewing machines for 80

attaching said strips to said soles have usually been constructed with a series of awls 11, 11 operating through openings in the presser foot 12 of the machine at a point reached by the work before it passes to the 85 sewing position at which the perforations in the work made by said awls 11, 11 are adapted to receive the sewing needles 13, 13. In the present instance three awls 11, 11 and three needles 13, 13 are used as it is desired 90 simultaneously to sew three lines of stitches but it is apparent that a greater or less number of said awls and needles may be used and that if the material to be operated on is suitable or if otherwise it is found desirable, the awls may be omitted.

Mounted in the machine is the usual plate member 14 having the guide 15 in which is slidably mounted the member 16 having the rotary sole edge guiding disk 17. This 100 member 16 is operated by means of the lever 18 pivoted to said member 16 and to a fixed part of the machine and is held in the adjusted position by means of the set screws 19 and 20 if desired. In the movement of sole A through the machine the edge of the sole rides against the rotary guiding disk 17, as is shown in Fig. 2, 105

whereby the spacing of the lines of stitches relative to the edge of said sole A is determined.

Adjacent the plate member 14 is mounted 5 the strip folding or manipulating guide and work support which comprises the lower member 21 having the channel 22 which has the shoulders 23, 23 gradually converging in the direction in which the work is fed 10 and terminating at the passage 24 of the work supporting element 25 of said member 21. This work supporting element 25 preferably is horizontal and in addition to the passage 24 has also the passage 26 both 15 of which are located with respect to the positions or paths in which the awls 11, 11 and the needles 13, 13 operate. Said passages 24 and 26 are open at their ends and the work supporting surface of said element 20 25 co-operates with the presser foot 12. To the lower strip guide member 21 is secured the upper guide member 27 having the depending rib 28 which extends into the channel between the shoulders 23, 23 and is gradually and progressively reduced in thickness 25 until it becomes the thin blade 28' and terminates at a point spaced from the passage 24.

Mounted on the plate 14 is the member 30 29 having the lip bending or turning finger 30 extending transversely of the passages 24 and 26 and spaced from the path of the needles 13, 13 to avoid a turning or bending of the insole lip during the sewing operation. This spacing of the finger 30 from the path of the needles may depend somewhat upon the material of the insole lip or upon the stiffness or other quality of said lip.

In the operation of the new machine a 40 strip B of suitable material, usually of canvas, is passed through the guide channel 22 of member 21. The forward end of said strip extends into and usually through opening 24 of the work supporting element 25. In such passage of strip B its cross sectional shape is changed to correspond somewhat 45 to the shape of said channel 22, so that said strip B is folded progressively to provide the duplex lip B' having the lateral extensions b, b which rest on the surface of the work support 25 while lip B' extends through the clearance afforded by the opening 24 of said work support in a line to be cleared by certain of said awls 11, 11 and 50 needles 13, 13 in the operation of the machine.

A suitable insole A is next placed and adjusted in the desired position with one of its surfaces bearing against said lateral 60 extensions b, b of lip B' and the presser foot 12 is brought to bear against said insole A substantially as shown in Fig. 1 and the sewing machine is operated in the usual manner to effect the perforating of the work 65 by the awls 11, 11 to facilitate the passage

through the work of the needles 13, 13 during the advancement of the work through the machine whereby three lines of stitches c, d and e are sewn, the lines of stitches c and d following closely the lines of juncture 70 between the duplex lip B' and its lateral extensions b, b and the line of stitches e being spaced from the line of stitches d toward the center of said insole A. In the progression of the work through the machine after said work passes the sewing position and preferably while the sole A still is subject to pressure of the presser foot 12 the duplex lip B' rides over the finger 30 whereby this lip B' is bent or folded over 80 the line of stitches d to, in effect, provide a channel member of which lip B' constitutes the upwardly inclined wall to which the welt and upper of the shoe are subsequently attached. 85

By the use of this machine the forming and sewing of the insole strip B to the insole A and the turning or bending of the lip to the desired position can be accomplished as a single operation. 90

Having thus described my invention I claim as new and desire to secure by Letters Patent:

1. A sewing machine comprising means to sustain a strip having a depending fold and a sole superposed on said strip, means to form a series of lines of stitches at the base of said fold, and means to turn said fold over one of said lines of stitches. 95

2. A sewing machine comprising means to sustain a strip having a depending fold and a sole superposed on said strip, means to form a series of lines of stitches at the base of said fold, and means to turn said fold over one of said lines of stitches in the advancement of the work. 100

3. A sewing machine having as a stitch forming element a series of laterally disposed needles and comprising means to fold and guide a strip of material to constitute a duplex lip passing between a pair of said needles, means to sustain members of said strip extending laterally from said lip during the sewing operation, and means to operate on said lip to bend the same laterally 110 after such sewing operation. 115

4. A sewing machine comprising means to guide and fold a strip in its progression toward the stitching position whereby said strip constitutes a longitudinal lip having lateral stitch receiving extensions, means to sustain said lateral extensions at the stitching position, means to prevent upward deflection of the work after said work leaves the stitching position, and means to operate 120 on said lip to deflect said lip laterally. 125

5. A sewing machine comprising a strip folding means terminating in a work support having at the stitching position a clearance for a depending fold formed from 130

said strip, means spaced from the stitching position to operate on said depending fold, and presser means acting on the work during said operation on said fold.

5 6. A sewing machine comprising a strip folding means having a channel to receive a fold of said strip and terminating in a work support having a needle passage in line with said channel and of a width to receive said fold in position to clear the needles, presser means for the work, and a finger extending transversely of said needle passage at a position to bear against and deflect said fold.

10

7. A sewing machine comprising a strip 15 folding means having a channel to receive a fold of said strip and terminating in a work support having a needle passage in line with said channel and of a width to receive said fold in position to clear the 20 needles, a lip turning member fixedly supported, spaced below the plane of said work support, and a presser guide extending above said work support and adapted to resist undue upward deflection of the work in passing over said lip turning member. 25

FRANK A. BRACKETT.
